UNITED STATES PATENT OFFICE.

THOMAS R. BROWN, OF NEW YORK, N. Y., ASSIGNOR, BY MESNE ASSIGNMENTS, TO NATIONAL PNEUMATIC COMPANY, A CORPORATION OF WEST VIRGINIA.

PNEUMATIC DOOR-OPERATING MECHANISM.

1,002,195.

Specification of Letters Patent. Patented Aug. 29, 1911.

Application filed March 15, 1906, Serial No. 306,127. Renewed March 12, 1909. Serial No. 483,058.

To all whom it may concern:

Be it known that I, THOMAS R. BROWN, a citizen of the United States, and a resident of New York city, in the county of New York and State of New York, have invented certain new and useful Improvements in Pneumatic Door-Operating Mechanisms, of which the following is a specification.

10 The invention relates to improvements in pneumatic door-operating mechanism, and it consists in the novel features, arrangements and combinations of parts herein-after described, and particularly pointed out 15 in the claims.

I present my invention herein as applied to a car for opening and closing the door thereof, and in its preferred embodiment my invention comprises means whereby 20 upon the movement of a control-handle to one position, compressed air will be caused to effect the unlatching and opening of the door and upon the movement of said handle to another position, the same air, then acting 25 against a surface of larger area, will be caused to effect the closing of the door, the latter becoming latched upon reaching its closed position. I thus utilize the air by which the door is opened for closing the 30 same and avoid the waste of air which would result if one supply of air from the reservoir were employed in opening the door and another supply thereof used for closing the door.

35 The mechanical devices for carrying my invention into effect may vary in many respects with the will of the manufacturer and the nature of the car or other body to be equipped with the same, but a very satisfactory embodiment of my invention will comprise, a manually operable control-valve to whose casing a pipe from a reservoir for compressed air will lead, a door-latching device to which a pipe from said casing will 40 extend and pass thence to a cylinder whose piston-rod is connected with the door, and a second pipe leading from said valve-casing to a cylinder whose piston is connected with the said piston-rod. Upon the movement of 45 the control valve to one position the compressed air will pass through its casing to the pipe leading to the door-latching device and after freeing the latch from locking engagement with the door, travel thence to 50 the first mentioned cylinder wherein it will

act to move the piston-rod in a direction to open the door and hold it open. Thereafter upon the movement of the control valve to another position the air supply pipe from the reservoir will be cut off and 55 the pipe leading from the valve-casing to the second or closing-cylinder will be placed in communication with the opening-cylinder and its supply pipe system, with the result that the air in said opening-cylinder and its 60 pipe system will expand into the pipe leading to said closing-cylinder and enter the latter, wherein, acting against a piston of larger area than that contained in the opening cylinder, it will reverse the movement 65 of the piston rod and effect the closing of the door, the air in the then connected system of pipes and cylinders exhausting through a suitable vent when the door reaches its closed position and the latch then 70 automatically passing into locking engagement with the closed door. The opening and closing cylinders may be located below or above the door as occasion may render most 75 desirable.

80 The invention will be fully understood from the detailed description hereinafter presented, reference being had to the accompanying drawings, in which:

Figure 1 is a side elevation, partly broken away, of a car equipped with door operating mechanism constructed in accordance with and embodying my invention; Fig. 2 is an enlarged side elevation, partly in section, of a portion of the door and the operating 85 mechanism connected therewith, the door being shown in closed position; Fig. 3 is an enlarged side elevation, partly in section, of the door and the operating mechanism connected therewith, the door being shown in open position; Fig. 4 is a vertical transverse section on the dotted line 3-3 of Fig. 2; Fig. 5 is a vertical transverse section on the dotted line 4-4 of Fig. 3; Fig. 6 is an enlarged vertical section, partly broken away, of the 90 manually operable control-valve and parts connected therewith, the section being on the dotted line 5-5 of Fig. 4; Fig. 7 is a top view, partly broken away, of the same, the control-valve operating handle being 95 shown by full lines in the position it will occupy when the door is in an open position and by dotted lines in the position to which it will be moved when the door is to be closed; Fig. 8 is an enlarged vertical section through the door-latching devices and parts connected therewith; Fig. 9 is a horizontal section through the control-valve and its casing on the dotted line 7-7 of Fig. 4, 100 the valve being shown in the position to 105 110

which it is moved when the door is to be closed; Fig. 8 is a like section, partly broken away, of the same, the valve being shown in the position to which it is moved when the door is to be opened, and Fig. 9 is a side elevation, partly broken away and partly in section, of a car whose door is equipped with operating mechanism embodying a modified form of the invention, Fig. 1 illustrating the location of the opening and closing cylinders below the plane of the door and Fig. 9 representing said cylinders arranged above the door.

In the drawings, 10 designates a portion 15 of a common car, 11 the door thereof, 12 the control-valve casing, 13 the supply pipe leading thereto from the reservoir, not shown, for compressed air, 14 the pipe leading from said casing to the casing 15 for 20 the door latching devices and extending thence (by a branch 30) to the outer end of the opening-cylinder 16, and 17 a pipe leading from the control-valve casing 12 to the outer end of the closing-cylinder 18. The 25 valve within the casing 12 is designated by the numeral 19 and the handle for operating said valve by the numeral 20. The adjoining ends of the cylinders 16, 18 are connected by an open frame 21 through which 30 passes the piston-rod 22, which, in the present instance, is in the form of a toothed bar carrying at one end, within the cylinder 16, a piston 23 and at its other end, within the cylinder 18, a piston 24. Between 35 the sides of the frame 21, above the piston-rod 22, is mounted a gear wheel 25 which is in engagement with the teeth of said piston-rod and also with a rack-bar 26 secured upon the lower edge of the door 11. The frame 21 is provided with upwardly extending arms 27 which straddle the lower edge of the door 11 and preserve the engagement of the rack-bar 26 with the gear-wheel 25.

The valve 19 is hollow and axially rotatable by means of the handle 20, and said valve has its interior chamber in constant communication with the supply pipe 13, which when the valve is turned to the position in which it is shown in Fig. 8, is placed in communication with the pipe 14 through the port 28 formed in the wall of said valve and the chamber 29 provided in the valve-casing 12, under which condition the compressed air will pass from the pipe 13 to the pipe 14 and thence to the latch casing 15, whence it will pass through the branch pipe 30 to the cylinder 16, for opening the door. When the valve 19 is turned to the position in which it is represented in Fig. 7, the port 28 becomes closed and a channel 31 on the exterior of the valve establishes a means of communication from the pipe 14 and its connections to the pipe 17 and cylinder 18, under which condition the compressed air

in the pipe 13 is cut off from the pipe 14 and the air in the pipe 14 and its connections may expand through the channel 31 into the pipe 17 and enter the cylinder 18, for closing the door.

The interior of the latch casing 15 is shown in Fig. 6, wherein it will be seen that said casing contains a cylindrical chamber 32 and a piston valve 33 therein, said piston-valve being located directly over the pipe 14 and adapted when in its lower position to close the end of said pipe and also the port 34 leading to the branch pipe 30. The piston-valve 33 is equipped with a stem 35 which projects upwardly and forms a seat for the spring-latch 36, which is pivoted upon the casing 15 and adapted at its free end to engage a catch-arm 37 fastened to the door. The spring 38 acts to press the latch 36 down upon the valve stem 35, and, as is obvious, the position of the latch is controlled by the position of said stem. When the control-valve 19 is turned to permit the compressed air to flow into the pipe 14 the pressure of said air will elevate the piston-valve 33 and consequently turn the latch 36 upwardly from the catch-arm 37 and free the door preparatory to the opening of the latter. The elevation of the piston-valve 33 also opens the port 34 in the latch casing 15 and thereby the compressed air is permitted to enter the branch pipe 30 and pass to the cylinder 16. So long as the pressure of the air is against the valve 33 the latter will be held in its elevated position, but upon the release of such pressure, which does not happen until the door 11 has been closed, the valve 33 will descend to its seat and the latch will automatically re-engage the catch-arm 37. The air which passes through the branch pipe 30 to the cylinder 16 acts against the piston 23 and drives the rod 22 into the cylinder 18, and during this movement of said rod the teeth thereon rotate the gear wheel 25 and the latter acting on the rack-bar 26 compels the door 11 to move to its open position. The door will be held in its open position so long as the pressure of the air is acting against the piston 23. To open the door therefore it is simply necessary for the attendant to turn the control-valve 19 to the position shown in Figs. 5 and 8 and thereby admit the compressed air to the pipe 14 leading to the latch mechanism and passing thence by a branch 30 to the cylinder 16. When it is desired to close the door the attendant will move the control-handle 20 to the position in which it is shown by dotted lines in Fig. 5 and thereby turn the valve 19 to the position in which it is shown in Fig. 7, thereby cutting off the supply pipe 13 and establishing communication between the pipe 14 and pipe 17; the compressed air in the pipe 14 and cylin-

der 16 will then expand into the pipe 17 and cylinder 18 and acting against the piston 24, which is of larger area than the piston 23, drive the rod 22 to its initial position, reversing the motion of the gear-wheel 25 and closing the door 11. When the door reaches its closed position, the piston 24 will have passed beyond the vent apertures 40 in the cylinder 18, and hence at such time the air in the cylinder 18 and connections leading thereto may exhaust through said apertures. As soon as the air in the pipe 14 has sufficiently exhausted, the piston valve 33 will descend and the latch 36 will engage the latch arm 37.

I provide the control-valve casing 12 with a vent 41 (Fig. 8) through which air in the cylinder 18 and pipe 17 may escape when the valve 19 is turned to admit air to the pipe 14 for opening the door.

The modification presented in Fig. 9 resides mainly in locating the opening and closing cylinders 16, 18 above the door and in connecting the piston-rod thereof by a fixed arm 42 to the door, and hence Fig. 9 will be understood without further description. The door shown in Fig. 9 will move toward the right on opening, while the door shown in Fig. 1 on opening moves to the left.

In both forms or arrangements of the mechanism shown the air used for opening the door is utilized to close the same, such air during the closing of the door acting against the piston 24 of larger area than the piston 23.

I do not limit my invention to any special details of form, arrangement or construction other than as may be indicated in the claims, since I am aware that my invention may be carried into effect in or by various forms and details of mechanisms and I desire to claim my invention broadly.

What I claim as my invention and desire to secure by Letters Patent, is:—

1. Door operating mechanism comprising a rod having rack teeth thereon and provided with a piston at each end, said pistons being of unequal area, a rack bar on the door, a gear wheel mounted in a fixed frame and respectively meshing with said rod and bar, cylinders inclosing said pistons, means for supplying air to one of said cylinders for acting against the piston therein and opening the door, and means for thereafter connecting said cylinders to supply the air under pressure to the other cylinder for acting against the piston thereon to close the door; substantially as set forth.

2. In a mechanism for operating a door, stationary cylinders arranged in line with each other, a piston operating in each cylinder, said pistons being of unequal area, a rack connecting said pistons, a valve mechanism for controlling the supply of operating medium, said valve arranged, when

actuated, to place said cylinders in communication with each other, and connections operated by the movements of said rack for moving the door.

3. In a mechanism for operating a door, in combination, power cylinders arranged in line with each other, a piston operating in each cylinder, said cylinders and pistons being of unequal area, a rack connecting said pistons whereby they move in unison, a valve mechanism operating, when actuated, to control the supply of operating medium, said valve mechanism being also arranged to open communication between said cylinders, means for exhausting said cylinders at the completion of the stroke in one direction only of the connected pistons, and devices actuated by the movements of said rack for moving the door.

4. In a mechanism for operating a door, in combination, cylinders of relatively different areas, a piston operating in each cylinder, a rack connecting said pistons whereby they move in unison, a valve mechanism for controlling the supply of operating medium and operating, when actuated, to open communication between said cylinders, the cylinder of larger area having exhaust openings arranged to be uncovered when the pistons complete their stroke, and means actuated by the movements of said rack for moving the door.

5. In a pressure actuated mechanism for operating a door, in combination, power cylinders, a piston operating in each cylinder, said pistons being connected together intermediate said cylinders to move in unison, means operated by said intermediate connections to move the door, and a valve mechanism for controlling the supply of pressure medium to said cylinders, one of said cylinders having exhaust openings arranged to be uncovered at one limit of movement of the piston operating therein.

6. In a mechanism for operating a door, a piston rod having a piston at each end, one of said pistons being of larger area than the other, cylinders inclosing said pistons, means intermediate said cylinders connecting said rod with the door, means for supplying compressed air to one of said cylinders for acting against the piston therein and opening the door, and means for thereafter cutting off the air supply and connecting said cylinder with the other cylinder so that the air used for opening the door may expand into said other cylinder and act against the piston of larger area therein for closing the door; substantially as set forth.

7. In a door operating mechanism, a piston rod having a piston at each end, one of said pistons being of larger area than the other, cylinders inclosing said pistons, means intermediate said cylinders connecting said

rod with the door, a manually operable control valve connected with a source of supply for the compressed air, a pipe leading from said valve to one of said cylinders for directing the air thereto to open the door, and a second pipe leading from said valve to the other cylinder wherein the said piston of larger area is located, said valve upon being operated to close the door being adapted to cut off the air supply and place said pipes into communication with each other, whereby the air used to open the door may expand into said second pipe and its cylinder and act against the piston therein to close the door, substantially as set forth.

8. In a door operating mechanism, a movable member having opposing faces of unequal area, means connected to said member intermediate said faces for moving the door, 20 a manually operable control valve connected with a source of supply for compressed air, a pipe leading from said valve to one of said faces for directing the air thereto for opening the door, and a second pipe leading 25 from said valve to the other of said faces, said valve when operated to close the door also operating to cut off the air supply and place said pipes in communication with each other.

30 9. In a door operating mechanism, in combination, stationary cylinders, a piston operating in each cylinder, said pistons being of unequal area and connected to move together, a valve mechanism for controlling 35 the supply of pressure medium to one of said cylinders to operate the pistons in one direction, and also operating to place said cylinders in communication with each other to operate the pistons in the other direction, 40 and connections intermediate said pistons and actuated by the movements thereof, for operating the door.

10. In a door operating mechanism, in combination, cylinders arranged in line with 45 each other, pistons operating in said cylinders, said pistons being of unequal area and connected to move together, a valve mechanism for controlling the supply of pressure medium to one of said cylinders, and the 50 communication of said cylinders with each

other, and means intermediate said pistons and connected to the door, to move the latter when said pistons are moved.

11. In a mechanism for operating a door, cylinders of unequal area, a piston operating in each cylinder, means connecting said pistons whereby they move in unison, a valve mechanism for controlling the supply of pressure medium to one of said cylinders to move the pistons in one direction, said valve 60 mechanism also operating to place said cylinders in communication with each other to move the pistons in the other direction, and connections intermediate said pistons, and operated by the movements thereof for moving the door. 65

12. In a mechanism for operating a door, in combination, power cylinders, a piston operating in each cylinder, said pistons being of unequal area and connected together to move in unison, a valve mechanism for controlling the supply of pressure medium to one of said cylinders, and the communication of said cylinders with each other, means for exhausting said cylinders at the completion of the stroke of the pistons in one direction only, and means connected intermediate the pistons, and operated by the movements thereof, for moving the door. 75

13. In a door operating mechanism, power 80 cylinders, connected pistons respectively operating in said cylinders, said pistons having oppositely presented faces of unequal area, means intermediate the pistons for connecting the same to the door, pressure supply 85 and exhaust connections, and means for controlling said connections, said means operating to supply pressure to the face of one of the pistons to move the door in one direction, and to place said cylinders in communication with each other to supply equal pressure to the faces of both pistons to move the door in the opposite direction. 90

Signed at New York city, in the county of New York, and State of New York, this 13th 95 day of March A. D. 1906.
